UNITED STATES PATENT OFFICE.

SAMUEL V. REEVES, OF HADDONFIELD, NEW JERSEY.

HOT-WATER STOVE.

1,156,929.

Specification of Letters Patent. Patented Oct. 19, 1915.

Application filed June 12, 1915. Serial No. 33,660.

To all whom it may concern:

Be it known that I, SAMUEL V. REEVES, a citizen of the United States, residing at Haddonfield, county of Camden, State of New Jersey, have invented a new and useful Hot-Water Stove, of which the following is a specification.

My present invention consists of a novel construction of a hot water stove in which the core of the water jacket is formed in a novel manner and wherein both ends of the water jacket have the same conformation so that the water jacket is reversible end for end and may be rotatably adjusted as desired in order to connect the jacket with the water conduits.

It further consists of a novel water jacket having its greatest diameter at the medial point equidistant from the top and bottom, the upper annular wall of said jacket converging upwardly from said medial point and the lower annular outer wall of said jacket converging downwardly from said medial point with the inclination of said upper and lower wall with respect to the longitudinal axis of the water jacket substantially alike and with the inner wall of the water jacket in proximity to the water conduits of greater thickness, in order to reduce to a minimum the variation in temperature of the water within the jacket due to the cold water passing into the water jacket.

It further consists of a novel construction and arrangement of a heat conveyer and water distributor which causes the cool water being admitted to first come into contact with a thicker wall of the water jacket.

Other novel features of construction and advantage will hereinafter more clearly appear in the detailed description of my invention.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a front elevation, partly in section, of a hot water stove em-

bodying my invention. Fig. 2 represents a top plan view of the water jacket. Fig. 3 represents a bottom plan view of the water jacket. Fig. 4 represents a bottom plan view of the top of the stove. Fig. 5 represents a top plan view of the bottom of the base of the stove with the legs removed. Fig. 6 represents a rear elevation of the heat conveyer and water spreader in detached position. Fig. 7 represents a sectional view of a portion of the water jacket and the water conduit communicating therewith, with the heat conveyer and water spreader in assembled position.

Similar numerals of reference indicate corresponding parts in the figures.

Referring to the drawings:—1 designates the base portion of the stove which is supported in any desired manner, for example, by means of the legs 2. The upper face of the base portion is provided with an annular groove 3 inwardly of which is an annular groove 4 adapted to receive the grate 5. The upper or fuel supporting surface of the grate is preferably in alinement with the top face 80 of the base portion 1. The base portion 1 is provided with a desired number of apertured ears or lugs 6, which are adapted to register with the apertured lugs or ears 7, so that the cylinder or water jacket 8 may 85 be connected with the base portion 1 by means of fastening devices 9 of any desired type. The bottom face of the water jacket 8 is provided near its inner periphery with an outwardly extending flange 10 which is 90 adapted to seat in the annular groove 3. The opposite end of the water jacket 8 has the same conformation, such end being provided with the outwardly extending flange 11, thereby forming a shoulder 12, it being 95 seen that the flange 10 at the opposite end of the jacket also forms a shoulder 13, so that the water jacket 8 may be reversed, if desired, without any change whatever in the construction of the base portion 1 or the top portion 14, which latter is adapted to seat on the shoulder 12 or the shoulder 13. The water jacket 8 is illustrated, in the present instance, as being provided with an inner cylindrical wall 15 and an outer annular wall 16. The outer annular wall has its greatest diameter at the medial point equidistant from the top and bottom of the water jacket. The upper annular outer wall of said jacket converges upwardly from the 105 110

medial point, while the lower outer annular wall of the water jacket converges downwardly from the medial point, and the inclination of the upper wall with respect to the longitudinal axis of the water jacket is the same as the inclination of the lower wall with respect to the longitudinal axis of the water jacket. If desired, the outer face of the water jacket may be provided with ribs 17 but these are not essential in all cases and may be dispensed with, if desired.

The upper end of the water jacket is provided with the apertured ears or lugs 18 which are adapted to receive fastening devices 19, which are connected with the top portion 14 in any desired manner. In the present instance, I have shown these fastening devices as consisting of bolts passing through apertured lugs or ears 32 on the top portion 14 and through the apertured lugs 18 and provided with nuts.

If the inner wall of the water jacket is made of uniform thickness throughout, the cool water which is being admitted decreases the temperature of the water within the water jacket, and in order to overcome this, the inner wall of the water jacket opposite a port 20 or 21 is made thicker, as at 22, (see Fig. 7). This increased thickness of the wall is preferably of greater diameter than the ports 20 and 21 or the conduits communicating therewith, 23 and 24, respectively. The portion 22 of the water jacket is the same at each end and it is therefore believed to be unnecessary to describe in detail the construction at each end. The portion 22 of increased thickness is provided in line with a conduit, such as for example, 23, with a threaded recess 25, adapted to receive the threaded end 26 of a heat conveyer and water spreader 27. This heat conveyer and water spreader comprises preferably a single piece of material having the rearward threaded portion 26 and intermediate portion or flange 28, the rear face of which forms a curved surface and the forward face of which has a conical contour, as at 29. Extending forwardly from the conical portion 29 is the cylindrical or other shaped extension 30, which is adapted to extend into one of the conduits 23 or 24. The intermediate portion 28 is provided with a series of apertures 31 therethrough.

It will be seen that the cool water entering through the conduit 23, for example, will be subject to the heat units radiating from the heat conveyer 27 and the water coming into contact with the conical shaped face 29 will be spread laterally so that it will first come into contact with the wall of increased thickness, 22. This heat conveyer is adjustably carried by the water jacket, so that the spreading action on the water may be varied as desired.

65 By reason of my novel construction of

water jacket and the arrangement of the grate, the hottest portion of the fire is in about the middle of the water jacket where the area of the body of the water is transversely the greatest. The cooler portions of the fire pot are at the top and at the bottom, whereby the body of water is of less transverse area, since the upper portion of the water jacket is heated by radiant heat and at the lower portion of the water jacket, there is an accumulation of ashes. By my present construction, I avoid a trapped or retarded circulation of the water which results in a strained or fractured water jacket, since in my device, the circulation is so rapid that there is but one determinate temperature in the entire water chamber, whereas in the prior art devices with which I am familiar, there are separate and distinct temperatures of the water, the result of which tends to retard the circulation of the water.

It will be seen that the rear face of the annular flange 29 and the heat conveyer and temperature modifier 27 has the same conformation as the juxtaposed face of the wall of the water jacket, and in the form illustrated, is curved to conform to the curvature of the thickened wall of the jacket.

The forward extension 30 of the heat conveyer and temperature modifier may extend any desired distance into the opening in the water jacket and the fitting connected therewith, so that the temperature of the water within the fitting will be modified before the water enters the chamber of the water jacket. This extension 30 is preferably provided with grooves or weakened portions 33 (see Fig. 7), so that the length of this extension may be varied in accordance with conditions and requirements met with in practice. For example, if the fitting, such as 23, forms an elbow, the extension 30 would be shorter than if a straight fitting was employed.

It will be seen that the water passing through the conduit or fitting 23 will pass through the apertures 31 and come into contact with the water which is in proximity to the inner wall of the water jacket which is of greatest thickness. The water will also be deflected and distributed by the conical face 29, so that the incoming water first comes into contact with a wall of increased thickness, the result of which is evident. It will be seen that by employing a wall of increased thickness near the outlet of the water chamber of the jacket, an increased amount of heat is present at such point which facilitates the circulation through the water jacket. The spreading of the water at the inlet to the water jacket may be varied by moving the heat conveyer 27 relatively to the inner wall 15 of the jacket.

Special attention is directed to the novel manner of forming the water jacket with the top and bottom faces thereof of the

same conformation and with a core chamber having its greatest diameter equidistant from the end thereof, whereby the jacket may be reversed end for end and also 5 rotatably adjusted in order to aline the water connections. Special attention is also directed to the increased thickness of the inner wall of the water jacket in proximity to the water connection in order to prevent 10 the deleterious cooling of the body of water in the water jacket. Special attention is also directed to the novel construction and arrangement of the heat conveyer and water spreader or distributer, so that the heat is 15 radiated into the incoming water and also preferably into the water which is passing from the water chamber of the jacket. I preferably employ a heat conveyer and distributer at the upper end of the water chamber, 20 but this may be omitted at such point, if desired.

The apertured lugs 7 are preferably located at right angles to the apertured lugs 18, so that when the water jacket is reversed end to end, the ports 20 and 21 will be brought into proper position for connection with the water conduits.

It will be apparent from the foregoing that a stove constructed in accordance with my present invention will produce a maximum amount of hot water with a minimum amount of fuel and it has been found in practice that very advantageous results can be obtained with a stove of this character, 35 even when the fire is banked.

It will now be apparent that I have devised a novel and useful hot water stove, which embodies the features of advantage enumerated as desirable in the statement of the invention and the above description, and while I have, in the present instance, shown and described a preferred embodiment thereof which will give in practice satisfactory and reliable results, it is to be 45 understood that the same is susceptible of modification in various particulars without departing from the spirit or scope of the invention or sacrificing any of its advantages.

Having thus described my invention, what 50 I claim as new and desire to secure by Letters Patent, is:—

1. A water jacket for a fire pot, comprising a casing having its inner wall of uniform diameter and its outer wall of greatest diameter at a medial point equidistant from its top and bottom, the outer wall of said jacket converging from said medial point toward the ends of the casing with the same inclination with respect to the longitudinal axis of the casing, and the end faces of said casing having the same conformation, whereby the water jacket is reversible end for end.

2. A water jacket for a fire pot, comprising a casing having its inner wall of uni-

form diameter and its outer wall of greatest diameter at a medial point equidistant from its top and bottom, the outer wall of said jacket converging from said medial point toward the ends of the casing with the same inclination with respect to the longitudinal axis of the casing, and the end faces of said casing each having an outwardly extending flange of the same conformation, whereby the water jacket is reversible end for end. 70 75

3. A water jacket, comprising a casing having a chamber provided with an inlet and an outlet, the inner wall of said casing opposite to said inlet being of increased thickness, and a heat conveyer and water distributer carried by the portion of said wall of increased thickness. 80

4. A water jacket, comprising a casing having a chamber provided with an inlet and an outlet, the inner wall of said casing in proximity to said inlet being of increased thickness, and a heat conveyer and water distributer adjustably carried by the portion of said wall of increased thickness. 85 90

5. A water jacket, comprising a casing having a chamber therein having its greatest diameter equidistant from the ends thereof and provided with an inlet at one end and an outlet at the other end, the inner wall of said casing opposite said inlet being of increased thickness and having a recess therein, and a heat conveyer and distributer comprising a member having one end adapted to engage said recess and its opposite end 95 100 extending into said inlet.

6. A water jacket, comprising a casing having a chamber therein having its greatest diameter equidistant from the ends thereof and provided with an inlet and an outlet, the inner wall of said casing opposite said inlet being of increased thickness, and a heat conveyer and distributer carried by said wall of increased thickness comprising a longitudinally extending member having intermediate the ends thereof a flange. 105 110

7. A water jacket, comprising a casing having a chamber therein having its greatest diameter equidistant from the ends thereof and provided with an inlet and an outlet, the inner wall of said casing opposite said inlet being of increased thickness, and a heat conveyer and distributer carried by said wall of increased thickness comprising a longitudinally extending member having intermediate the ends thereof a flange provided with apertures therethrough and having its forward face conical. 115 120

8. A water jacket, comprising a casing provided with a chamber having its greatest diameter intermediate the ends thereof and with an inlet to said chamber, the inner wall of said casing opposite said inlet being of increased thickness and provided with a recess in alinement with said inlet, and a heat 125 130

- conveyer and distributer comprising a rearwardly extending portion adjustable in said recess, a forwardly extending portion, and an intermediate portion comprising an annular flange provided with a forwardly extending conical face to cause the incoming water to first contact with said conveyer and next with the portion of the wall of increased thickness.
- 10 9. A water jacket, comprising a casing provided with an inner wall of substantially uniform diameter and with an outer wall having its greatest diameter at a medial point equidistant from its top and bottom and provided with an inlet at one end and an outlet at its other end, the inner wall of said casing in alinement with said inlet and with said outlet being of increased thickness, and a heat conveyer located in proximity to each wall of increased thickness and extending outwardly therefrom.
- 10 10. A water jacket, comprising a casing having a water chamber provided with an inlet and an outlet, the inner wall of said
- 5 casing opposite said inlet and said outlet being of increased thickness.
11. A water jacket, comprising a casing having a water chamber provided with an inlet and an outlet, a heat conveyer and distributer extending from the inner wall of the jacket into said inlet and provided with an annular flange having its inner face conforming to the contour of the inner wall of the jacket and having its outer face conical.
- 11 12. A water jacket, comprising a casing having a water chamber provided with an inlet and an outlet, the inner wall of said casing opposite said inlet and outlet being of increased thickness, and a heat conveyer carried by each wall of increased thickness 35 and projecting into the juxtaposed opening and provided with weakened portions near its end, whereby the length of said conveyer may be varied.
